(57) **CLAIM**

The ornamental design for a pair of gloves, substantially as shown and described.

DESCRIPTION

FIG. 1 is a rear perspective view of a first embodiment of a right-handed glove embodying the new design, showing the backhand surface thereof;

FIG. 2 is a rear elevation view of the glove of FIG. 1;
FIG. 3 is a front elevation view of the glove of FIG. 1, showing the palm surface thereof;

FIG. 4 is a left side elevation view of the glove of FIG. 1;
FIG. 5 is a right side elevation view of the glove of FIG. 1;
FIG. 6 is a bottom plan view of the glove of FIG. 1, looking into the open end. The unevenly-incremented broken line shown just inside the opening of the glove defines the bounds of the design and forms no part of the claim;

FIG. 7 is a top plan view of the glove of FIG. 1.

FIG. 8 is a rear perspective view of a second embodiment of a right-handed glove embodying the new design, showing the backhand surface thereof;

FIG. 9 is a rear elevation view of the glove of FIG. 8;
FIG. 10 is a front elevation view of the glove of FIG. 8, showing the palm surface thereof;

FIG. 11 is a left side elevation view of the glove of FIG. 8;
FIG. 12 is a right side elevation view of the glove of FIG. 8;
FIG. 13 is a bottom plan view of the glove of FIG. 8, looking into the open end. The unevenly-incremented broken line shown just inside the opening of the glove defines the bounds of the design and forms no part of the claim; and,

FIG. 14 is a top plan view of the glove of FIG. 8.

It is to be understood that each of the gloves described herein also has a counterpart glove for the opposite hand, the views of which are mirror images of the glove that is shown.

The broken lines shown on the glove itself illustrate unclaimed features. The broken line shown on the interior of the glove defines the bounds of the claimed design and forms no part thereof.
